COIN SLIDE STRUCTURE

Louis M. Hall, Fort Thomas, Ky., assignor to The
Monarch Tool & Manufacturing Company,
Cincinnati, Ohio, a corporation of Ohio

Application July 17, 1934, Serial No. 735,705

5 Claims. (Cl. 194—92)

This invention relates to an improvement in a coin slide structure and the present application is a continuation in part of my copending application Serial Number 709,621, filed February 3, 5 1934.

An object of the present invention is to provide means in connection with a slug-rejecting structure for enhancing the effectiveness and positive operation thereof to reject slugs of various kinds.

10 More specifically, an object of the invention is to provide the coin-receiving aperture of a coin slide with a wrench or grip, whereby a chisel dog may more effectively intercept and stop the entry of a slug into the coin-operated release mechanism of a vending machine.

15 The foregoing and other objects are attained by the means described herein and disclosed in the accompanying drawing, in which:

Fig. 1 is a plan view of a coin slide structure 20 embodying the invention.

Fig. 2 is a side view of the Fig. 1 device.

Fig. 3 is a plan view of a double-acting ratchet member or pawl which cooperates with notches formed along one side edge of the slide.

25 Fig. 4 is a fragmental plan view of the slide or actuating member.

Fig. 5 is a cross-sectional view taken on line 5—5 of Fig. 4.

The means of this invention is designed to preclude 30 improper operation of a coin slide structure such as is applied to vending machines, and to preclude jamming and possible injury to the structure by reason of the insertion of slugs therein. Like the device of my aforesaid copending patent application, the present device includes a slug cutter which dents or shaves the slug edge so that said cutter or other parts of the mechanism may move into position for precluding a full operative stroke of the handle member or actuator.

40 It is to be understood that the present device may include the same means to eject all slugs or improper coins as set forth in my aforesaid copending application, supplemented, however, by the improvement described hereinafter.

45 The present improvement will of course be found applicable to other forms of coin slide structures which include cutters or dogs that operate upon the edges of the coins or slugs, as will be apparent.

50 In the drawing, 12 indicates a guide member or plate which has suitable longitudinal bearing or guide channels 13 and 14 for slidably receiving the side edges 15 and 16 of a coin slide or coin advancing member 17. The member 17 preferably is in the form of a substantially flat longi-

tudinal strip having the forward handle end 18 and a rear end 19. The coin slide is adapted to be advanced from the inoperative extended position of Fig. 1 to a fully advanced position, (to be described later), at which the handle end is disposed a short distance from the mounting plate 20, and at which position the coin is delivered by the slide to any suitable receiver or till at the right-hand side of the mounting plate. The guide member 12 will be seen to extend both 10 forwardly and rearwardly of the mounting plate 20.

In the normal or inoperative position of the coin slide, (Fig. 1), an aperture 21 therein, for the reception of nickels, registers substantially 15 with an exposed cut-away portion 22 of the part 12 so that such coin may be placed within the aperture 21 and be advanced by the slide while resting upon the bottom wall 23 of the guide plate or member 12. A finger hole 24 is provided in 20 the bottom wall 23 to enable the operator to easily remove a coin inadvertently placed in the opening 21, before advancement of the slide to an appreciable extent.

It is of importance to note that the aperture 25 21 of the slide is located off-center, (Fig. 3), and that it has a mouth or cut-out at the edge 16 of the slide bounded by a pair of opposed abutments 25 and 26. Abutment 25 is a dog stop, and is formed in part by the edge 16 of the slide. The 30 abutment 26 is a dog guide, and is located inwardly of the slide edge 16 but associated therewith, in a sense, by reason of the connecting incline or track portion 27. The distance between the abutments 25 and 26 is less than the diameter of aperture 21. The abutments are adapted to cooperate with the stop end 28 and the chisel or cutter part 29 of a slug intercepting dog 30, in a manner to be described later.

Reference is made to the copending application above noted, for details of the mechanism for ejecting the coins at the rear of the device, as that portion of the mechanism is not necessarily included in the present invention. For the same reason, a detailed description concerning 45 the magnet 31, and the coin slide pawl or ratchet means 32—33—34—35, need not be given except to state that the pawl or ratchet means functions to permit but one complete reciprocation of the 50 slide 17 for each proper coin inserted in the opening 21.

The trigger member 36 which is pivoted upon a bracket 37 of the top plate 38, as indicated at 55 39, has a vertically movable nose 40 adapted to enter the holes in washer-like slugs, or the open-

ing 21 when no coin or slug is present, to preclude full advancement of the slide as explained in detail in the copending application.

In accordance with the present invention, the coin receiving aperture 21 of the slide 17 is provided with friction means, preferably, though not necessarily, in the form of serrations or tooth-grips 41 disposed approximately diametrically opposite to the dog guide or abutment 26. The grips 10 or wrench elements 41 may be sharpened or not, as desired, and they perform the function of precluding rotation of a slug or improper sized coin when the chisel edge of the dog 30 engages such slug or improper coin. The chisel edge of 15 the dog thereby assuredly dents or shaves the edge of the improper coin or slug and jams it to preclude full advancement of the slide. The teeth or grips 41 may be formed during the operation of punching out the opening 21, or they 20 may subsequently be formed in the opening. In any event they perform to frictionally hold a coin or slug, as follows.

The dog 30, which is pivoted upon the body of the device as at 42 in the plane of slide 17, has a 25 flat guiding portion 43 which normally rests against the side edge 16 of slide 17 with the result that the stop end 28 of the dog is held out of the path of movement of the slide abutment 25. As the slide is advanced, however, the dog 30 element or guide 43 slides inwardly over the incline 21, due to the yielding action of a spring 44, to place the abutment 28 of the dog in position to engage the abutment 25 of the slide and to thereby arrest the advancing movement of 35 the slide. The foregoing described action results when no coin or slug is placed in the coin slide aperture 21.

When a proper sized slug of cardboard, lead, or other comparatively soft material is placed in the receiving aperture 21, and the slide is advanced by the operator, the cutter point or chisel edge 29 will move inwardly over the incline 21 and will dig into, shave, or indent the edge of the soft slug thereby permitting the stop end 28 of dog 30 to move into arresting engagement with the abutment 25 of the slide member 17. During the digging, shaving, or indenting of the slug by the chisel edge of the dog, the slug is precluded from rotating in the aperture 21 by reason of the friction or gripping means 41 thereby avoiding all possibility of the chisel edge to over-ride the edge of the slug and permit its passage into the mechanism of the device.

When a proper coin is placed within the aperture 21, advancement of the slide causes the abutment 43 of the dog to ride over the periphery of the coin edge, thereby maintaining the stop end 28 out of the path of movement of the slide abutment 25. A coin smaller than the proper one 50 naturally will not extend from the open edge of the receiving aperture 21 sufficiently to force the guide 43 outwardly and remove the stop 28 from the path of the slide abutment 25.

Perforated, thin, or magnetic coins or slugs 65 are rejected by the dog 40 or magnet 31, as explained in the aforesaid copending application.

What is claimed is:

1. As a new article of manufacture, a coin slide for coin controlled devices, comprising a straight substantially flat longitudinal plate having front and rear edges, a plurally notched longitudinal side edge on the plate, said notches being of uniform depth, the endmost ones of the plurality of notches being longer than the intermediate 75 notches, a second side edge on the plate in sub-

stantial parallelism with the first mentioned side edge, said second side edge being cut away intermediate the front and rear edges to provide an open sided coin-receiving aperture, a transverse abutment at the forward portion of said aperture, an incline adjacent to the rearward portion of said aperture, and means associated with said coin-receiving aperture to resist rotational movement of a coin-shaped slug therein.

2. In a device of the class described, the combination of a slide provided with an aperture to receive a coin or slug, a guide for said slide and means to permit a full stroke of predetermined length when said slide contains a coin, and to prohibit the predetermined stroke when no coin is in said slide aperture, said stroke prohibiting means including a chisel edged dog lying in the plane of the slide and at one side thereof to sink its chisel edge into the edge of a soft slug when such slug is advanced by the slide, means including serrations in the coin slide aperture to resist rotation of such slug in the coin slide aperture while the chisel edge of the dog sinks into the edge of said slug, and means operating to simultaneously positively prevent longitudinal advancement of the slide and limit the extent to which the chisel edge may enter the slug, thereby to preclude extreme slug mutilation and possible slug jamming.

3. In a device of the character described, the combination of a longitudinally movable slide provided with an open sided aperture to receive a coin, a guide for said slide, and means prohibiting a full stroke of said slide, including a dog having a chisel edge and a stop edge lying in the plane of the slide and at one side thereof to sink its chisel edge into the edge of a soft slug when such a slug is placed within the open sided aperture and exposed to the chisel edge by advancement of the slide, an abutment on the 40 slide adjacent to the open sided aperture to strike and engage the abutment of the dog for arresting movement of both the slide and the dog, thereby to cause the chisel edge of the dog to enter but slightly into the edge of the slug, and gripping means extended into the coin slide aperture in position to contact the slug and resist rotation thereof in the aperture as the chisel edge of the dog sinks into the edge of the slug upon advancement of the slide.

4. In a coin controlled device of the character described, the combination of a guide element including guide means, a coin advancing slide having a side edge, movable along said guide means from an inoperative retracted position to a fully 55 advanced position, said coin advancing slide having formed therein an off-center coin receiving aperture cut away at said side edge of the coin slide to expose part of the periphery of a coin or slug fitted within said receiving aperture, a 60 dog including a cutting edge disposed for engaging the exposed peripheral part of a coin or slug advanced by the coin slide, whereby a slug of soft material will have its periphery shaved or nicked as such soft slug is advanced by the coin 65 slide during movement of said slide toward the fully advanced position above mentioned, friction means extending into the coin receiving aperture to contact the slug and resist rotation thereof during the shaving or nicking operation, 70 and means operating to preclude movement of both the dog and the coin slide to such an advanced position as would cause the cutting edge to mutilate a slug to the extent of jamming the mechanism.

8,010,360

5. In a coin controlled device of the character described, the combination of a guide element including guide means, a coin advancing slide having a side edge, movable along said guide means from an inoperative retracted position to a fully advanced position, said coin advancing slide having formed therein an off-center coin receiving aperture cut away at said side edge of the coin slide to expose part of the periphery of a coin or slug fitted within said receiving aperture, a dog including a cutting edge disposed for

engaging the exposed peripheral part of a coin or slug advanced by the coin slide, whereby a slug of soft material will have its periphery shaved or nicked as such soft slug is advanced by the coin slide during movement of said slide toward the fully advanced position above mentioned, and means operating to sufficiently limit movement of both the dog and the coin slide, to preclude substantial mutilation of a soft slug.
